CLAIM

The ornamental design for a solar powered light, as shown and described.

DESCRIPTION

FIG. 1 is a perspective view of a solar powered light; FIG. 2 is a front view of the solar powered light of FIG. 1;

FIG. 3 is a left side view of the solar powered light of FIG. 1;

FIG. 4 is a right side view of the solar powered light of FIG. 1;

FIG. 5 is a back view of the solar powered light of FIG. 1; FIG. 6 is a top view of the solar powered light of FIG. 1; and, FIG. 7 is a bottom view of the solar powered light of FIG. 1.

The broken lines shown on the drawings depict portions of the solar powered light that form no part of the claimed design.
